UNITED STATES PATENT OFFICE.

LAWRENCE COOPER WALSH, OF WEBSTER, MASSACHUSETTS.

RAILWAY-GATE.

SPECIFICATION forming part of Letters Patent No. 295,696, dated March 25, 1884.

Application filed October 22, 1883. (No model.)

To all whom it may concern:

Be it known that I, LAWRENCE COOPER WALSH, of Webster, in the county of Worcester, and State of Massachusetts, have invented a new and useful Improvement in Railway-Gates, of which the following is a full, clear, and exact description.

Reference is to be had to the accompanying drawings, forming part of this specification, in which similar letters of reference indicate corresponding parts in both the figures.

Figure 1 is a side elevation of my improved gate, parts being broken away. Fig. 2 is a sectional end elevation of my improvement, taken through the line *x x*, Fig. 1.

The especial object of this invention is to provide a simple and reliable means for closing railroad-crossings upon the approach of trains, and preventing people from attempting to cross railroad-tracks in front of moving trains.

The invention consists in the construction and arrangement of parts, as will be herein-after fully described and claimed.

25 A represents a railroad-track, and B is a railroad-crossing.

Upon the opposite sides of the crossing B, and at the side of the track A, are set two posts, C, at a distance apart about equal to twice the width of the said crossing B.

To the tops of the posts C are attached side boards, D, to which is attached a roof, E.

F is a gate, which may be formed of horizontal bars connected by chains, or in any other suitable manner, and which is made of a length equal to the breadth of the crossing. In the case of wide crossings two gates F can be used, meeting each other end to end at the center of the crossing.

40 The space between the side of the crossing B and the farther post C is closed by a fence, G, of any suitable construction.

To the top bar of the gate F, at points preferably at a distance from the ends of the gate equal to one-third the length of the said gate, are attached the ends of chains H, the upper ends of which are connected by clevises I, or other suitable means, with two pulleys, J. The pulleys J rest and roll upon a bar or

track, K, which is pivoted at one end to and 50 between the side boards, D. The track K, near its other end, is connected by a link, L, or other suitable connection, with the end of a lever, M, which passes through a slot in the post C, and is pivoted to the said post. With 55 this construction, when the free end of the track K is lowered below a horizontal position, the pulleys J will roll down the said track, carrying the gate F to the side of the crossing and leaving the said crossing unobstructed. When the free end of the track K is raised above a horizontal position, the pulleys J will roll down the said track, closing 60 the gate.

N is a catch hinged to the side boards, D, in 65 such a position that when the free end of the track is raised to close the gate the said end will strike the inclined lower end of the catch N, push back and pass the said end, and be caught by the shoulder of the said catch and 70 supported, locking the gate closed.

To the free end of the lever M and the lower end of the catch N are attached, respectively, the ends of the wires O P, which may be led to the station, office, or some other desired 75 place where they can be operated by the railroad officials to open and close the gate; or the said wires can be connected with levers or other mechanism placed in such positions as to be struck at the proper time by the 80 engine, and operated to open and close the gate.

I have shown and described my gate as being applied to railroad-crossings, but it can be used with equal advantage in various other 85 places.

I am aware that it is old to construct gates provided with pulleys to roll on pivoted tracks, said tracks being provided with cords and levers to operate them, and also provided with 90 latches for holding them in position and suitable cords for operating said latches, and I do not desire to claim, broadly, such constructions.

Having thus fully described my invention, 95 I claim as new and desire to secure by Letters Patent—

The combination, with the gate F, the pul-

leys, connections between said gate and pulleys, and the track K, pivoted at its outer end, and provided near its free end with a link, L, of the pivoted lever M, connected to the track by said link, and the vertical pivoted latch N, for engaging the free end of the track, cords or wires O P, secured to the free end of the lever and lower end of the latch,

respectively, and a suitable frame-work for supporting the above devices, substantially as set forth.

LAWRENCE COOPER WALSH.
